(57) **CLAIM**

The ornamental design for an anti-nesting device for a post frame building, as shown and described.

DESCRIPTION

FIG. 1 is a perspective view showing our new design. FIG. 2 is an end view thereof, the opposite end view being a mirror image view thereof.

FIG. 3 is a right side view thereof.

FIG. 4 is a left side view thereof.

FIG. 5 is a top plan view thereof.

FIG. 6 is a bottom plan view thereof.

FIG. 7 is an end view of a second embodiment of an anti-nesting device for a post frame building as installed on to a framing strip shown in dashed lines, the strip being shown only to illustrate an environment in which our new design may be used, and forming no part of the invention hereof; and,

FIG. 8 is a perspective view thereof as installed on to said strip shown in dashed lines.
